UNITED STATES PATENT OFFICE.

LÜDWIG SCHÖN, OF VIENNA, AUSTRIA-HUNGARY, ASSIGNOR TO SIEGFRIED HERLINGER, OF VENICE, CALIFORNIA.

POCKET-IGNITER.

970,649.

Specification of Letters Patent. Patented Sept. 20, 1910.

Application filed December 15, 1909. Serial No. 533,172.

To all whom it may concern:

Be it known that I, LÜDWIG SCHÖN, a citizen of the Empire of Austria-Hungary, residing at Vienna, in the Empire of Austria-Hungary, have invented certain new and useful Improvements in Pocket-Igniters, of which the following is a specification, reference being had therein to the accompanying drawing.

10 This invention relates to a pocket igniter of that class which combines with a wick saturated with a combustible liquid an igniting mechanism, one of the objects of this invention being to eliminate phosphorus or other flame producing chemical agents and the cumbersome mechanism required for combusting such agents.

Another object of this invention is to provide in a pocket igniter, a simple mechanism for producing a spark by frictional abrasion, thereby avoiding the dangers incident to that class of substances which produce flame either by friction or detonation.

With these and other objects in view, this invention consists of the features, details of construction and combination of parts described in connection with the accompanying drawing and then more particularly pointed out in the claims.

30 In the drawing, Figure 1, is a sectional side elevation of an igniter embodying the invention. Fig. 2, is a sectional elevation on lines A—B Fig. 1. Fig. 3, is a transverse section on lines C—D Fig. 1, and Fig. 35 4, is a side elevation of the igniter.

Reference being had to the drawing, *a* designates a casing having a hinged cover *b*, adapted to be forced open by a spring *f*, and kept closed by a snap *r*, operable from the outside of the casing by a knob *y*, which extends through the casing. A pin *h*, fixed between the sides of the casing *a*, has loosely mounted thereon a small toothed wheel *m*, to which a ratchet wheel *n*, is rigidly secured. A pawl-lever *d*, having pivotally secured thereto a spring-actuated pawl *c*, is also mounted on said pin *h*, and is connected with the cover *b*, by a link *p*. The said toothed wheel *m*, its ratchet wheel *n*, and the pawl-lever *d*, are loosely mounted on said pivot pin *h*. When the cover *b*, is forced open under the tension of the spring *f*, the pawl *c*, on the pawl lever *d*, engages the teeth of the ratchet wheel *n*, and rotates the same together with the toothed wheel *m*, in

the direction of the arrow *l*. When, however, the cover is closed, the pawl *c*, glides over the teeth of the ratchet wheel *n*, without causing it or the toothed wheel *m* to rotate, said latter wheel being held against rotation by the pyrophorous alloy, as will appear more fully hereinafter.

Part of the front side of the casing *a*, is cut away and the bottom is wholly removed in order to admit of the insertion of a liquid hydrocarbon lamp *v*, into the casing *a* from below. The edges of the cut-away portion of the front side of the casing *a*, overlap the front side of the lamp *v*, which is narrower than the hollow space in the casing *a*. The bottom of said lamp is provided with flaps *z*, on the sides thereof, which flaps *z*, project beyond the body of the lamp and serve to close the opening in the bottom of the casing.

75 In a socket *g*, secured to the sides of the casing *a*, and immediately below the toothed wheel *m*, is a piece of pyrophorous alloy *u*, which is in constant engagement with said toothed wheel *m*, such engagement with the periphery of said toothed wheel being insured by one end of a bell-crank lever *k*, which is pivoted in the sides of said casing *a*, while the other end of said lever *k*, is under the tension of a helical spring *i*, which is connected therewith. The other end of said helical spring *i*, is connected with a screw bolt *t*, which passes through a hole provided in one of the projecting flaps *z*, of the lamp *v*. Engaging the threaded shank of said screw bolt is a nut *w*, by the manipulation of which the tension of the spring *i*, and the force with which the piece *u*, of the pyrophorous alloy is pressed against said toothed wheel *m*, may be controlled. Said nut *w*, also serves to hold the lamp *v*, in its position in the casing.

90 Liquid hydrocarbon is supplied to the lamp *v*, through the orifice in the bottom thereof, which orifice is closed by a screw plug *o*.

100 The operation of the igniter is substantially as follows:—The push knob *y*, being pressed inwardly by the thumb or other member, releases the cover *b*, which then flies open under the tension of the spring *f*, causing thereby, through its connections a rotation of the small wheel *m*, in the direction of the arrow. The abrasion of the 110

toothed wheel *m* with the pyrophorous alloy resulting from the rotation of the said toothed wheel *m*, produces sparks, which are transmitted in the direction of rotation of the said wheel and of the wick *j*, of the lamp *v*, which wick is thereby ignited. The said wheel *m*, is provided with teeth primarily to effect a continuous production of sparks during its rotation against the pyrophorous alloy, which would not be possible were the periphery thereof smooth.

The closing of the cover *b*, places the elements *c*, *d*, and *p* in operative position.

When it is desired to remove the hydrocarbon lamp *v*, from the casing *a*, the nut *w* is unscrewed and the lamp may then be extracted from the casing.

The piece *n*, of pyrophorous alloy may readily be replaced after the lamp has been withdrawn. To this end it is only necessary, as is obvious, to press the lever *k*, downwardly thereby to remove the end thereof from the socket *g*, whereupon a fresh piece of alloy may be inserted.

25 Claims.

1. In a pocket igniter, the combination with a casing, a hinged cover, a spring adapted to fling the cover open and means for locking and unlocking the cover in its closed position, of a toothed wheel revolubly mounted in the casing, a ratchet wheel rigidly secured to the toothed wheel, a pawl lever and pawl adapted to reciprocate by the side of the ratchet wheel, a spark producing alloy normally held in contact with said toothed wheel, and a link connecting the pawl lever to the hinged cover, whereby by the rotation of said toothed wheel a spark is produced.
2. In a pocket igniter, the combination with a casing of a toothed wheel mounted therein, means for rotating the wheel, a guiding socket secured to the sides of the casing below the wheel, a piece of pyrophorous alloy inserted into this socket, a two-armed lever pivoted within the casing and having the end of one arm placed below the piece of pyrophorous alloy, a coiled spring connected with the other arm of the lever, a screw bolt connected with the said spring and having its free end projecting through a hole in the bottom of the casing, and a draw nut screwed upon the said free end of the bolt, substantially as and for the purpose described.

3. In a pocket igniter, the combination with a bottomless casing having a recessed front side, of a toothed wheel revolubly mounted therein, means for rotating the wheel, a guiding socket secured to the sides of the casing below the wheel, a piece of pyrophorous alloy inserted into this socket, a two-armed lever pivoted within the casing and having one end placed below the piece of pyrophorous alloy, a benzin holder of less

breadth than the casing and adapted to be inserted through the lower opening of the casing, laterally projecting flaps of the bottom of the benzin holder, a coiled spring connected with the other arm of the said lever, a screw-bolt connected with the said spring and having its free end projecting through a hole of a projecting flap of the benzin holder, and a draw nut screwed upon the said free end of the bolt, substantially as and for the purpose described.

4. An igniter comprising a casing having a spring-actuated cover hingedly secured thereto, a liquid hydrocarbon receptacle fitting in said casing, means to lock said receptacle in said casing, a wick extending from said receptacle, a toothed wheel loosely journaled in said casing and provided with a ratchet wheel, a spark producing alloy in proximity to said wick, means to normally hold said alloy in contact with said toothed wheel, means controllable by the movement of said cover in one direction to rotate said toothed wheel and produce a spark in the direction of and ignite said wick, said alloy serving to hold said toothed wheel inactive during the movement of said cover in the opposite direction.

5. A device of the character described comprising a casing having a spring-actuated cover hingedly secured thereto, a receptacle fitting in said casing, means to hold said receptacle in said casing, a wick extending from said receptacle, a socket in said casing, a spark producing alloy in said socket, a toothed wheel journaled in said casing, a ratchet wheel rigidly secured to said toothed wheel, a lever provided with a pawl to engage said ratchet wheel when moved in one direction, a link connected with said lever and hinged cover and controllable by said cover to rotate said toothed wheel and produce a spark in the direction of and ignite said wick, and means to hold said alloy in contact with said toothed wheel.

6. An igniter comprising a casing having a spring actuated cover, a rotatable element journaled in said casing, a spark producing alloy in contact with said element, means to regulate the frictional contact of said alloy with said element, a wick, a pawl lever in operative relation to said element to rotate the same in one direction and produce a wick igniting spark, and a link connected with said pawl-lever and said cover and controllable by said cover to actuate said pawl-lever.

7. An igniter comprising a casing having a spring-actuated cover hingedly secured thereto, a toothed wheel journaled in said casing, a ratchet wheel on said toothed wheel, a lever provided with a pawl, said pawl having normal engagement with said ratchet wheel, a link connected to said lever and with said cover and controllable by said

cover to actuate said toothed wheel, a socket in said casing, a spark producing alloy in said socket, regulable means in said casing and in engagement with said alloy to normally hold said alloy in contact with said toothed wheel, and a lamp removably fitted in said casing and having a wick extending therefrom and in proximity to said alloy.

8. An igniter comprising a bottomless casing having a spring-actuated cover hingedly secured thereto, a receptacle fitting in said casing and having a wick extending therefrom, a socket in said casing, a spark-producing alloy in said socket, a toothed wheel 10 loosely journaled in said casing and pro-

vided with a ratchet wheel, a mechanism connected with said cover and in operative relation to said ratchet wheel and controllable by the movement of said cover in one direction to rotate said toothed wheel and 20 produce a spark in the direction of said wick, and regulable means to constantly insure contact of said alloy with said toothed wheel.

In testimony whereof I hereunto affix my 25 signature in presence of two witnesses.

LÜDWIG SCHÖN.
